UNITED STATES PATENT OFFICE.

SILAS A. SHELLY, OF HARRISBURG, PENNSYLVANIA.

CIGAR-ROLLING BOARD.

SPECIFICATION forming part of Letters Patent No. 657,013, dated August 28, 1900.

Application filed April 19, 1900. Serial No. 13,501. (No model.)

To all whom it may concern:

Be it known that I, SILAS A. SHELLY, a citizen of the United States, residing at Harrisburg, in the county of Dauphin and State 5 of Pennsylvania, have invented certain new and useful Improvements in Cigar-Rolling Boards; and I do declare the following to be a full, clear, and exact description of the invention, such as will enable others skilled in 10 the art to which it appertains to make and use the same.

The invention relates to cigar-rolling boards of that character in which suction is employed to hold the wrapper with a gentle 15 adhesiveness to the board to permit of the free manipulation of both hands in the act of wrapping the cigar.

The object of the invention is to simplify the construction and to provide a machine 20 of this character which may be made at a greatly-reduced cost and perform its work in an efficient manner.

With this object in view the invention consists in certain features of construction and 25 combination of parts, which will be herein-after fully set forth.

In the accompanying drawings, Figure 1 is a perspective view of a cigar-maker's bench or table, illustrating the application of my 30 invention; and Fig. 2 is a longitudinal vertical sectional view, upon an enlarged scale, through the rolling-board.

Referring to the drawings, 1 denotes a bench or table of any well-known or approved construction, and 2 denotes the rolling-board. 35 This board is formed with a longitudinal aperture 3, in which is fitted the upper end of a suction-chamber 4, the lower end of which communicates with an exhaust-pipe 5, which 40 may be provided with any suitable means for producing an exhaust and which is also provided with a controlling-valve 6. The aperture is provided with a ledge 7, upon which is seated, flush with the surface of the rolling-board, a foraminous or perforated plate 8, 45 which is held in place by screws 9, that pass downward through the plate and the flanged upper end of the suction-chamber into the ledge.

50 In operation properly-shaped cigar-wrappers are furnished to the operator, who places them one at a time on the perforated plate.

The cigar-bunch to be wrapped is now placed in position over the wrapper, and one end of the wrapper is engaged with the cigar-bunch. 55 In rolling the bunch the wrapper will be pulled from the perforated plate as the cigar is being wrapped, the suction being of sufficient strength to hold the wrapper on the plate and acts as a tension to the wrapper as 60 it is being wound about the cigar. The valve may be operated in any desired manner, either by a rod 10, which projects within convenient reach of the hand of the operator, or by a treadle which may extend underneath the 65 bench or table.

From the foregoing description, taken in connection with the accompanying drawings, the construction, operation, and advantages of the invention will be readily understood 7c without requiring an extended explanation.

The device is exceedingly useful for the purpose for which it is designed and may be placed upon the market at a comparatively small cost.

Having thus fully described my invention, what is claimed as new, and desired to be secured by Letters Patent, is—

1. In a cigar-rolling board, the combination of a rolling-board having an aperture, the 80 wall of which is provided at its upper edge with a surrounding ledge, a suction-chamber fitting within said aperture and adapted to be applied and removed through the top thereof, said chamber being provided at its 85 upper edge with flanges resting upon the ledge and having flaring walls extending below the board and forming a contracted bottom, a valve-chamber applied to the said contracted bottom, a valve in said chamber, means 90 for operating the valve, an exhaust-pipe connected to the valve-chamber, a perforated plate seated upon the flanges of the suction-chamber, and fastening devices common to 95 said flanges and perforated plate for securing the same to the ledge, substantially as set forth.

2. In a cigar-rolling board, the combination, with a work-table provided with an opening, and a rolling-board located adjacent to said opening and provided with an aperture, of a suction-chamber seated within said aperture and provided at its lower end with a central valve-chamber, a perforated plate secured 100

to the rolling-board at the top of the aperture, a valve in said valve-chamber, and a rod connected with said valve and having an upwardly - extending portion projecting through said opening in the table and terminating in a handle, substantially as set forth.

In testimony whereof I have hereunto set my hand in presence of two subscribing witnesses.

SILAS A. SHELLY.
